UNITED STATES PATENT OFFICE

DANIEL E. HENNESSY, OF CAMBRIDGE, MASSACHUSETTS, ASSIGNOR OF SIXTY PER CENT TO LEWIS-SHEPARD COMPANY, OF WATERTOWN, MASSACHUSETTS, A CORPORATION OF MASSACHUSETTS

PROTECTIVE WRAPPER FOR SPRINGS AND THE LIKE

Application filed December 16, 1927. Serial No. 240,484.

This invention relates primarily to improvements in spring covers of the type which are usually employed to enclose the leaf springs of vehicles for the purpose of protecting the same from water, dust, and the like, and also to retain the lubricating material between the leaves of the spring.

In its broader sense the invention relates also to a novel wrapper which may be produced as an article of manufacture and employed not only as a wrapping for leaf springs, but for various other obvious purposes.

Various covers for leaf springs have been employed including fabric tapes having adhesive coatings of the type employed to cover electric connections. Such covers have been unsatisfactory and of short life because the cover does not yield uniformly in conformity to the flexing of the springs, and the unequal strains thereby imposed upon the tape causes it to unwind or become ineffective within a short time.

Other forms of covers have been employed, such as rubberized fabric casings, steel casings, and the like. Such constructions, however, are expensive and are of a more or less bulky and unpleasing appearance.

An object of the present invention is to provide a relatively simple and inexpensive and efficient spring cover which can be readily applied.

A further object of the invention is to provide a spring cover of weatherproof elastic material which will closely enclose the spring and will yield in conformity with the flexing of the spring.

A further object of the invention is to provide a spring cover of this character which will exclude water, dust, and other foreign materials from the spring leaves, and which will also prevent the escape of suitable lubricants from the spring.

These and other objects and features of the invention will more fully appear from the following description and the accompanying drawings and will be particularly pointed out in the claims.

In the drawings:

Fig. 1 is a side elevation of the end por-

tion of one of the side frames of a vehicle with a usual type of leaf spring secured thereto and showing a preferred type of spring cover embodying the invention in the process of being applied thereto;

Fig. 2 is a detail view in perspective of a portion of a spring cover having a body of elastic material, such as rubber composition, which may be vulcanized, and having homogeneous surface layers of like material of a tacky consistency, such for example as uncured rubber;

Fig. 3 is a perspective view of a sheet of homogeneous elastic material, such as uncured rubber, supported upon and detachably adherent to a sheet of flexible material providing an article of manufacture which can be folded or rolled into packages suitable for storage and transportation.

As illustrated in Fig. 1 of the drawings the end portion 1 of the side frame is provided with a bracket 2 to which one end of the long leaf 3 of a usual leaf spring is secured, the opposite end of the leaf spring being flexibly secured to the end of the frame by a shackle 4. The spring comprises a series of supplemental leaves 5 of any desired number superimposed upon the lower side of the long leaf 3.

The spring wrapper embodying the invention comprises a sheet 6 of weatherproof elastic material which enwraps the spring and may extend either from end to end, as shown, or may comprise sections on either side of the usual spring chair. The sheet which constitutes the wrapper for the spring desirably is of substantially homogeneous elastic material presenting a tacky surface which when overlapped will cohere with a like surface of the sheet upon which it is superimposed, and thereby form an effectively integral cover, or casing.

In the illustrative embodiment of the invention shown in Fig. 1 the sheet is long and narrow and is spirally wrapped upon the spring with the portion of one spiral overlapping the preceding spiral, thereby producing a wrapper which fits and conforms to the surface of the spring. It will, however, be understood that the sheet may be

cut to suitable form by dies, or otherwise, and applied to the spring with sufficient portions of the surface of the sheet overlapping to insure a complete covering of the spring 5 and sufficient area of contact between the surfaces to insure permanent cohesion therebetween, and form an integral casing.

The covering desirably is applied to the spring under tension and the elasticity of the material will maintain such tension upon 10 the wrapper which will always cause it to bind tightly upon the spring. By virtue of the elasticity of the covering and of the tension which is maintained, the cover will 15 yield in conformity with the flexing of the spring with no substantial slipping between the cover and the spring. The spring cover when applied under tension aids in maintaining proper contact between the spring 20 leaves and in insuring proper interleaf friction between said leaves.

The sheet forming the spring cover may be made of any suitable, substantially homogeneous, elastic composition, the surfaces of 25 which are adapted when superimposed to cohere and thus form a spring cover comprising a substantially integral mass of material enwrapping the spring.

Preferably the material of the spring cover 30 is uncured rubber or a rubber composition presenting a surface of uncured rubber which, before its application to the spring, is in a tacky condition. A suitable rubber composition for such a sheet may be made 35 largely from reclaim rubber, as for example, 50 parts of reclaim tread, 50 parts of reclaim friction, 4 parts of magnesium oxide, 6 parts of lime, 10 parts of calcium carbonate. However, other suitable proportions of rubber, 40 either pure or reclaim, and other ingredients, may be employed to provide a sheet having proper elasticity, and the other characteristics herein described, in accordance with the knowledge of those skilled in the art of rubber manufacture.

In Fig. 2 of the drawings a sheet is illustrated which comprises a central body of rubber composition 7 presenting opposite surfaces 8 and 9 of uncured rubber. The body 7 may be formed as a separate sheet 50 and so treated or vulcanized as to provide a high degree of elasticity. The surface covering 8 and 9 may be applied of uncured rubber, substantially homogeneous in composition with that of the sheet 7. Preferably, however, the entire sheet is made up of homogeneous uncured rubber composition 10 as illustrated in Fig. 3, in which the sheet is supported upon a flexible base sheet 11 for 55 purposes which will hereinafter more fully appear.

When the sheet is wrapped upon the spring the superimposed surface of uncured rubber will cohere permanently, while the exposed surfaces will soon become "air dried" or "air

vulcanized" and present a smooth appearance which is not tacky or sticky. A spring cover of this character is weatherproof, is not effected by graphite which is commonly used as a lubricant for the spring, nor is it unfavorably effected by such vegetable lubricants as palm oil, castor oil, and the like, so that the spring can be properly lubricated before the application of the cover thereto.

It will be obvious that a spring cover can be readily applied to the spring without the necessity of employing skilled labor. The cover conforms closely to the form of the spring, is not bulky, and presents a pleasing appearance both as to form and as to surface. It can be made in any color which will correspond to or harmonize with the color of the chassis or body of the vehicle. Obviously any desired number of sheets or layers may be applied as may be required or desirable. It can be readily removed and a new cover applied. Sheets of suitable material embodying the invention may be made in any desired length so that it is unnecessary to 90 provide sheets of particular size for different sizes and characters of springs. The elasticity of the sheet permits it to be wrapped around the usual spring clips, thereby avoiding the necessity of their removal as is required in many types of spring covers.

A further object of the invention is to provide a sheet of the character described as an article of manufacture. Such a sheet is illustrated in Fig. 3 in which a sheet of elastic material 10 is shown, such as a homogeneous sheet of rubber having tacky surfaces one of which is supported upon and adheres to a flexible sheet of suitable material or base 11 having a smooth surface from which the sheet 105 of elastic material can be readily detached. When the sheet is thus supported the sheet and the supporting base can be rolled up into a convenient package, like a roll of adhesive tape. It can be readily stored and the protection from the air afforded by the flexible base 110 will prevent substantial deterioration of the material of the elastic sheet. When the sheet is to be used the roll can be unrolled, the elastic sheet stripped from its supporting base, and applied to the spring in the manner above described.

It will be obvious that an elastic sheet of this kind, particularly when of rubber or rubber composition, may be used as a wrapper 115 for electric conductors and for many other purposes.

It will, therefore, be understood that the particular embodiments of the invention and the uses thereof specifically disclosed herein 125 are illustrative and not restrictive of the meaning and scope of the following claims.

Having thus described the invention, what is claimed as new, and desired to be secured by Letters Patent, is:

1. A spring cover comprising a sheet of substantially homogeneous rubber composition under tension enwrapping the spring, with overlapping portions of said sheet united by cohesion.

5 2. A spring cover comprising a substantially homogeneous elastic sheet, under tension, of uncured rubber and presenting tacky surfaces, enwrapping the spring, with overlapping portions of said sheet united by cohesion.

10 3. A spring cover comprising a homogeneously elastic sheet of uncured rubber composition presenting tacky surfaces spirally, under tension, the spring, with overlapping portions of successive spirals of said sheet united by cohesion.

15 In testimony whereof, I have signed my name to this specification.

CERTIFICATE OF CORRECTION.

Patent No. 1,757,633.

Granted May 6, 1930, to

DANIEL E. HENNESSY.

It is hereby certified that error appears in the printed specification of the above numbered patent requiring correction as follows: Page 3, line 15, claim 3, before the word "under" insert the word "enwrapping"; and that the said Letters Patent should be read with this correction therein that the same may conform to the record of the case in the Patent Office.

Signed and sealed this 24th day of June, A. D. 1930.

**M. J. Moore,
Acting Commissioner of Patents.**
